SHOE TOE LINING TRIMMING MACHINE

John M. Ewart and Lester S. Macdonald, Beverly,
Mass., assignors to United Shoe Machinery
Corporation, Flemington, N. J., a corporation
of New Jersey

Application June 20, 1950, Serial No. 169,188

9 Claims. (Cl. 12—83.5)

1

This invention relates to machines for trimming the lasting margin of the lining at the toe end of a partially fabricated shoe, an operation usually performed after the sides of the shoe have been lasted and in preparation for the lasting of the toe portion. A trimming machine embodying the present invention is accordingly to be used on shoes of the McKay or other types in which the lasting margins at the toe, after satisfying pulling-over requirements, need to be reduced in width and bulk.

Trimming of these toe margins eliminates a fabric surplus which, if not severed properly, would be unevenly distributed and creased during toe lasting to prevent securing the smooth and neatly finished appearance that is desired. Generally the plane of the trimming is preferably spaced heightwise of the plane of the toe of the insole by approximately the thickness of the upper. In addition to leaving a rather uniform margin by means of clean cutting, it is important that the trimming band extend rearwardly nearly to the endmost side lasting fastenings so as to avoid producing folds which would bulge in those areas of the finished shoe.

The outer layer of shoe material at the toe end, commonly of upper leather, will hereinafter be referred to as "upper," and the term "lining" will, for convenience, be used to refer collectively to the layers backing the upper, these layers often including what is normally termed lining plus the intermediate doubler and stiff box toe.

It is an object of the present invention to provide an improved trimming machine for rapidly performing the described severing in an entirely satisfactory manner on a partially fabricated shoe in bottom-down position, which machine shall be of relatively simple construction and easily operable.

To the accomplishment of this objective, and in accordance with one feature of the invention, there are provided means for clamping the strip of lining to be trimmed, a member engageable with the bottom of the shoe to support its toe portion, and a cutter carriage having a fulcrum cooperative with said member whereby the shoe may be rocked heightwise of said means to tension the upper and lining against the toe portion of the last while the trimming knife severs the clamped strip.

Another feature of the invention resides in the provision of means for moving the cutter carriage toward and from a shearing bed comprising toe wiping segments, said means serving successively to bring into operation said segments, cooperating work spreading and pressing members, the trimming knife, and lining tensioning mechanism engageable with the shoe bottom forepart.

These and other features of the invention including novel arrangements of parts will now

2

be described in detail in connection with a preferred illustrative embodiment thereof, reference being had to the accompanying drawings, in which:

Fig. 1 is a left-hand side elevation of a machine in which the invention is embodied, portions of the stand and treadle connections being broken away;

Fig. 2 is an enlarged sectional view of the operating portion of the machine as seen in Fig. 1, the section being taken along the longitudinal center line, and a shoe being shown in initial operating position;

Fig. 3 is a sectional view similar to Fig. 2 but further enlarged and indicating the shoe and the machine in a subsequent stage of the trimming operation;

Fig. 4 is a plan view of the operating portions of the machine;

Fig. 5 is a continuation of Fig. 4 and shows portions of the drive mechanism;

Fig. 6 is a perspective of spreaders and plow shown in Fig. 4;

Fig. 7 is a plan view of a portion of the mechanism viewed in Fig. 4, the elements of Fig. 6, and other elements and wiping mechanism being omitted for clarity;

Fig. 8 is an enlarged plan of a portion of the machine operating on an unlasted, spread toe margin;

Fig. 9 is an inverted plan of a portion of the work in position for trimming;

Fig. 10 is an enlarged horizontal section of cutter clamping mechanism shown in Figs. 1, 2, and 3;

Fig. 11 is an exploded view, in perspective, of adjusting mechanisms shown in Fig. 4;

Fig. 12 is a perspective of a shoe forepart prior to having its toe trimmed by the illustrative machine; and

Fig. 13 is a perspective similar to Fig. 12 showing the forepart after it has been trimmed in this machine.

The machine comprises a main frame 10 (Fig. 1) fixedly mounted on a stand 12 or any preferred stationary supporting means of convenient height. A pair of oppositely disposed bracket portions 14 of the frame 10 extend upward therefrom and are bridged by a horizontal U-shaped shearing bed member 16 detachably secured thereto as by bolts 17 (Figs. 4 and 8). A cutter carriage 18 is arranged for movement forwardly and rearwardly between the portions 14 and beneath the member 16 together with several work engaging elements hereinafter to be described. The carriage 18 supports, by means of stud bearings, eight rollers 20 (only the four on one side being shown in Fig. 1), four being in engagement with the upper and four with the lower sides of a horizontal guide plate 22 extending from the

front to the rear of the machine and secured to the frame 10 by screws 23 (Figs. 4 and 7).

For enabling an operator conveniently to position the shoe relatively to the operating instrumentalities a toe abutment 24 (Figs. 1, 2, and 3) is mounted for adjustment toward or from the shearing plane of the member 16, the latter supporting a block 26 having an inclined bore threaded to receive a knurl-headed shank 28 of the abutment 24. A heel rest 30 at the front of the machine includes a split clamp 32 integral with the frame 10, a vertically adjustable clevis 34 supported thereby and a T-shaped member 36 adjustably held by said clevis for engagement with the rearward portion of a shoe bottom.

A pair of upright members 38 affixed to the front of the frame 10 are bored to receive a pin 40 on which a slightly resilient and tongue-like insole toe support 42 is pivotally mounted and normally extends over the cutter carriage 18 toward the shearing bed member 16.

Wipers 44 and 46 (Figs. 4, 8, and 9) are flat segmental plates arranged for movement widthwise of the member 16 and occupy recesses formed transversely in its lower face. The lower surface of these wipers 44 and 46, together with that face, constitute the smooth shearing bed against which the toe portion of an upper is to be spread as will be described. The wipers 44, 46 are each provided with a guide slot 48 for receiving one of the bolts 17, and the adjacent ends of the wipers are curved toward one another to provide a formation adapted to accommodate the toe end of a shoe. Ears 50, 52 (Figs. 8 and 9) respectively project from the wipers 44, 46 and, when the latter are suitably moved, are engageable with the bottom of a lasted shoe at its marginal portions.

For moving the wipers 44 and 46 toward one another for a purpose later to be explained, the cutter carriage 18 is provided with oppositely disposed cam slots 54, 56 in which cam followers 58, 60 are respectively located. Since adjusting and actuating means for both wipers are similar, only the arrangement relating to wiper 44, cam 54, follower 58, and associated parts (as shown in Figs. 4 and 11) will be described. The follower 58 is rotatably mounted on a shank 59 threaded into the bifurcated end of a member 62 and the latter is provided with a cylindrical leg internally threaded to receive an adjusting screw 64. A sleeve 65 receives the leg telescopically and is pinned against telescopic movement with respect to the screw 64. An element 66 has an elongated slot 67 for receiving the shank 59 and is movable in a mortise formed longitudinally in the sleeve 65. A vertical cylindrical portion 68 of the element 66 is pivotally mounted on a hinge pin 70 supported by the bracket 14. Turning the screw 64 accordingly is effective to position the shank 59 in the slot 67 and thus changes the distance between the axis of the follower 58 and the hinge pin 70. An arm 74 also pivotally mounted on the pin 70 and integral with the cylindrical portion 68 carries in an elongated slot 76 a roller 78 having its stud bearing secured to the wiper 44 as by a nut 80. The screws 64 will both be turned appropriately to adjust the degree of swing imparted to the arms 74, respectively, and hence control the extent of widthwise closing movement of the wipers 44, 46.

A pair of work spreading member 82, 84 (Figs. 2, 3, 4, and 6) are respectively supported for horizontal pivotal movement on a pair of pins 86 secured to the front of a generally flat plate 88.

The plate 88 has a depending cylindrical projection 89 received by the carriage 18. A pin 90 affixed in this projection extends into a slot 92 formed in the carriage 18. Three compression springs 94 fitted in recesses of the carriage 18 urge the plate 88 upwardly, its lower limit being determined by the pin 90 and slot 92, and its upper limit by the heightwise adjustment afforded by a screw 96 threaded into said projection and having its head engaging shoulders of the carriage 18. A raised portion 98 of the plate 88 (Fig. 6) constitutes a flat symmetric plow having a protruding nose portion adapted to underlie even the narrowed widths of toe portions. Each of the spreaders 82, 84 has a raised lip portion 100 engageable with the work and corresponding in contour with its side of the plow 98.

For moving the spreaders 82, 84 apart each is provided with a roll 102 that engages the walls of cam slots 104, 106 (Fig. 4) formed in levers 108, 110 respectively. These levers are fulcrumed on pins 112 respectively mounted on a rearward raised portion of the frame 10. Rolls 114, 116 (Figs. 4 and 7) respectively depend from the forward ends of the levers 108, 110 and ride in opposite sides of a V-shaped cam track 116 secured to the carriage 18.

The preferred trimming tool 118 is a slightly dished rotary disc type of knife (Figs. 1, 2, 3, and 4) mounted centrally on the carriage 18 and having its circular cutting edge arranged in shearing relation with the lower face of the cutting bed member 16. The cutting edge is substantially concentric with the trailing edge of the plow 98. The diameter of the knife 118 is preferably equal to the widthwise dimension of the largest toe portion to be operated upon. A flat annular band 120 circumscribed by the cutting edge is helpful in partially supporting a shoe during the trimming operation. The knife 118 is secured to the upper end of a vertical shaft 122 by means of a screw 124, and a pin 126 projecting into the knife 118 from a flange of the shaft 122 locks the latter against rotation relatively to the knife 118. The shaft 122 is rotatable in a sleeve bearing 128 journaled in the carriage 18. Means are provided to adjust the knife 118 heightwise of the shearing plane of the member 16 and wipers 44, 46 so as to accommodate different thicknesses of upper. Thus, as shown in Fig. 10, a pair of clamping members 130 slidably within a bore of the carriage 18 engage opposite portions of the bearing 128. A bolt 132 threaded into one of the members 130 will, when turned, move the members 130 into and out of clamping relation with the bearing 128 to support the knife heightwise as desired. For purposes hereinafter to be described a pinion gear 134 is affixed to the lower end of the shaft 122, being held thereon by a collar and pin 136. The teeth of this gear 134 are arranged to mesh with those of a horizontal rack 138 fixedly secured within a slot of the guide plate 22 by screws 139. Also rotatably mounted on the carriage 18 but arranged to follow in the operative path of the knife 118 during a toe trimming operation is a projection preferably in the form of a fulcrum roll 140 (Figs. 1, 2, 3, and 4). The roll 140 is horizontally disposed with its perimeter extending somewhat above the shearing level of the knife 118 and arranged to be progressively engageable with the tongue-like toe support 42.

Power means for operating the machine comprises a motor 142 (Fig. 1) bolted to the stand 12, 75 a drive belt 144, and a pulley 146 driven thereby

and mounted on a drive shaft 148. The latter is supported in bearings 150 bolted to a rear extension of the stand 12. Crank arms 152 (Fig. 5) are respectively secured to the ends of the shaft 148 and each carries a ball bearing 154. Connecting rods 156, 158 are provided with sockets to receive the bearings 154 and also respectively to receive ball pins 160, 162. The latter are respectively affixed by pins 154, 166 (Fig. 4) to guide rods 168, 170 which are slidably mounted in block bearings 172, 172 secured to the stand 12. The rods 168, 170 also extend through sleeve bearings 174, 174 respectively integral with the bracket portion 14 and their forward ends are bridged by a cross member 176 secured thereto by pins 178, 178, said cross member being affixed to a front portion of the carriage 18.

While the motor 142 is normally in continuous operation, a single revolution (in the direction shown by the arrow in Fig. 1) of the drive shaft 148 is utilized to move the carriage 18 through a trimming stroke relative to the shearing bed member 16 and back to the initial starting position shown in Fig. 1. Accordingly, a single revolution clutch mechanism of conventional design is provided and will be briefly described with reference to Figs. 1 and 5. A hub 180 having peripherally spaced blocks 182 affixed therein is normally freely revolvable with the pulley 146 and is backed by one of the bearings 150. A collar 184 affixed to the shaft 148 by a pin 186 is bored slidably to receive a shank portion 188 of a clutch cam 190. The shank 188 may extend between two blocks 182 and has a bore across which a pin 192 extends. A compression spring 194 within said bore bears on the collar 184 and against the pin 192 to urge the shank 188 into a recess between the blocks 182. A clutch pin 196, treadle-operated as will be described, normally is in raised position as seen in Fig. 5 wherein it engages the clutch cam 190 to hold the shank 188 out of driving engagement with the blocks 182. When depressed, however, the clutch pin 196 permits the spring 194 to move the shank 188 into driving relation between the blocks 182. On being raised again the pin 196 engages the cam 190 to shift the shank portion 188 out of driving engagement, and a key 198 axially slidable in the collar 184 under the influence of a cushioning spring 200 serves to hold the clutch pin in steady engagement with the cam 190.

The clutch pin 196 extends through the stand 12 (Fig. 1) and is provided with a spring 202, an adjacent fixed collar 204 and a fixed collar 206. Above the spring 202 the clutch pin 196 is received by a bracket portion of one of the bearings 150, said portion serving to limit down movement of a stop 207 secured to the clutch pin. A rod 208 supported by the stand 12 serves as fulcrum for a bell crank 210, one arm of which extends between the collars 204 and 206 for connection with the pin 196. The bell crank 210 is actuated to raise or lower the pin 196 by a series of connecting members including a lever 212, bell crank 214, treadle rods 216 and treadle 218. A tension spring 220 having one end affixed to the stand 12 is connected to the rods 216 so as to yieldingly support the treadle 218 in a normally inoperative position.

By means now to be described, the clutch pin 196 is yieldingly returned to its upper or starting position when a cycle has been started. A pin 222 (Figs. 1 and 5) affixed in an arm of the bell crank 210 is arranged to be accommodated by a notch formed in the lever 212. A bifurcated

link 224 pivotally connected to one of the bearings 154 has elongated slots 226 for receiving a stud 228 mounted on the lever 212. A tension spring 230 (Fig. 1) connects the lever 212 and the bell crank 210. After the bell crank 210 and the lever 212 have been actuated against the resistance of the spring 230 to start the cycle, the stud 228 will be lifted by engagement with the lower ends of the slots 226, the link 224 being swung by a crank arm 152. The lever 212 is consequently raised to free its notch from the pin 222 and thereby permits the spring 230 to rock the bell crank 210 and raise the clutch pin 196 against the resistance of the spring 202.

15 To start the machine on its trimming cycle the operator will trip the clutch mechanism by momentarily stepping on the treadle 218. The resultant motion of the clutch pin 196 permits a single revolution of the shaft 148 as described 20 and, by means of moving in phase the crank arms 152, connecting rods 156, 158, and guide rods 168, 170, the cutter carriage 18 is moved toward and then away from the shearing bed member 16. During its movement of translation with the carriage 18, the trimming knife 118 is also rotated in the shearing plane by reason of relative movement of the pinion 134 and rack 138 thereby effecting a draw cut on the work as well as shearing action.

25 30 Before the knife 118 engages the work, however, the power means are operative properly to position the unsecured material against the shearing bed. As the carriage 18 advances with the plate 88, the cam tracks 116 swing the arms 108, 110 apart and they in turn respectively operate to move the spreaders 82, 84 widthwise of the toe. As a consequence, the lips 100 of these spreaders are moved outwardly, i. e., from their positions as shown in Fig. 4 to those shown in 35 Fig. 8, to progressively spread and flatten the work against the shearing bed as shown in Fig. 9. The springs 94 yieldingly urge both the lips 100 and the closely following plow 98 upward, thereby smoothing and clamping the lining 40 against the shearing bed and just ahead of the oncoming knife 118.

45 At the start of this spreading action the wipers 44, 46, selected and suitably adjusted to conform with the toe contours to be trimmed, are actuated 50 by the carriage motion to close about the toe as seen in Figs. 8 and 9. They thus advantageously hold the stock in close contact with the last and the toe perimeter of the insole, and the ears 50, 52 serve evenly to fold the surplus material close 55 to the endmost side lasting fasteners inserted in the lasting margins. As the knife 118 advances, the fulcrum roll 140 pushes upwardly on the toe support 42 (Fig. 3) and thereby causes the last yieldingly to tension the clamped lining 60 and upper downwardly over the toe contour. To maintain this tension during trimming, which is desirable in order to obtain lining severance along a line close to the insole profile, an operator 65 will prevent the shoe from rising off the heel support 36 by bearing down somewhat on the back part of the last.

70 On return of the carriage 18 to its starting position the wipers 44, 46 and spreaders 82, 84 are caused to resume their initial positions by reason of the reverse movement of their respective cams. The shoe which was inserted in the machine when its toe portion appeared as shown in Fig. 12 may then be removed in the trimmed condition shown in Fig. 13. It is to be noted that 75 the surplus lining, which was allowed to fall

away from the knife 118 upon severance, has been trimmed so that but little lining extends from the insole in the vicinity of the endmost side lasting fasteners and only to the extent of the thickness of the upper, approximately, around the perimeter of the toe, thereby providing an excellent condition for toe lasting.

Having described our invention, what we claim as new and desire to secure by Letters Patent of the United States is:

1. A machine for trimming surplus lining from the unlasted toe of a partially fabricated shoe in bottom-down position, comprising a shearing bed, said bed including movable wipers cooperative to receive the perimeter of the toe, a carriage movable toward and from the bed, a circular knife mounted on the carriage for rotation in a plane substantially parallel with that of the shearing bed, lining spreading members yieldably mounted on the carriage to engage the unlasted margin ahead of the knife, and means for moving the carriage, said means being effective to rotate the knife and operate said wipers and spreading members.

2. A machine for trimming unlasted marginal toe material comprising a shearing bed including cooperative wipers engageable with the upper at the toe, a carriage movable relatively to said bed and having members arranged to spread the unsecured toe lining thereon, a rotary knife mounted on the carriage to follow said members in shearing relation to the spread lining, the knife being spaced heightwise from said bed by the thickness of the upper, and means for moving said carriage, said means serving to close said wipers on the upper about the toe and operate said members.

3. A trimming machine comprising a frame, shoe engaging means mounted on the frame including a flat insole supporting member, a carriage guided for movement relative to said means by said frame, clamping means mounted on the carriage and arranged to clamp a strip of lining projecting from the toe portion of the insole, a knife mounted on the carriage and having a cutting edge adapted to sever the clamped strip, said member being movable heightwise of the shoe engaging means by said carriage to tension the clamped strip to be severed.

4. In an upper trimming machine having a frame, mechanism for moving a cutter carriage movable with respect to the frame and in shearing relation to a toe receiving member, means mounted on the carriage for clamping the margin of the upper to be trimmed, an insole supporting member engageable with the toe portion, and a fulcrum mounted on the carriage to move the insole supporting member heightwise of the toe receiving member during operative movement of the carriage, whereby the clamped marginal material is tensioned before being shorn.

5. A machine for trimming the marginal toe portion of a partially fabricated shoe comprising a frame, a toe receiving shearing bed mounted on the frame, a trimming knife rotatable in shearing relation to the bed, a carriage guided by the frame for movement with the knife toward and from the bed, means operated by said carriage for spreading and clamping the marginal toe portion outwardly on the bed, and a member moved by the carriage into engagement with the toe portion of the shoe bottom for tensioning the margin to be trimmed.

6. A machine for severing surplus marginal toe material from a shoe, comprising a shearing

member including wipers movable widthwise of the toe portion to engage the upper, an insole support, a carriage movable with respect to the insole support, a trimming knife carried by the carriage beneath said support and into and out of shearing relation with said member, spreaders progressively engageable with the marginal toe lining, and mechanism operable by movement of the knife into said shearing relation and in advance thereof to close said wipers and operate said spreaders.

7. In a machine for trimming surplus toe material, a cutter carriage, a toe receiving bed, trimming means movable by the carriage into shearing relation with said toe receiving bed, and means operated by the carriage for tensioning the unsecured toe upper and lining against said bed in advance of shearing action by the trimming means, said tensioning means including inwardly movable wipers engageable with the toe upper, outwardly movable spreaders engageable with the toe lining, and means for moving the toe portion of the insole heightwise of said bed as the trimming means advances.

8. In a machine for trimming surplus marginal material from the toe of a shoe on a last having a frame, a shearing bed supported thereby and having a portion conforming with said toe, a carriage reciprocably mounted on the frame, a circular knife borne by the carriage into shearing relation with said bed, a flat insole supporting member pivotally mounted on the frame and extending above the knife and toward the bed, means operable by the carriage to spread the marginal material ahead of the knife, wiping means operable by the carriage to restrain upper material adjacent the perimeter of the toe of the insole, and means on the carriage engageable with said insole supporting member to tension the upper over the toe portion of said last before the knife shears said marginal material.

9. A trimming machine for operating on marginal toe material of shoes in bottom-down position comprising a shearing bed, said bed including wipers cooperatively movable to embrace a toe portion at its perimeter, means movable transversely of said perimeter to hold the work margins spread outwardly against the underside of the bed, a tongue-like member mounted for pivotal movement about a horizontal axis and extending lengthwise of the shoe, said member being adapted to engage the insole at the toe portion, trimming means movable beneath said toe portion engaging member and in shearing relation to the bed, and means operative by advancement of the trimming means to raise said member relatively to the path of the trimming means whereby the shoe bottom is urged heightwise to tension the upper material being trimmed.
